(57) **CLAIM**

The ornamental design for an ice crampon shoe protector, as shown and described.

DESCRIPTION

FIG. 1 is a perspective view of an ice crampon shoe protector showing my new design;

FIG. 2 is another perspective view thereof;

FIG. 3 is a bottom view thereof;

FIG. 4 is a top view thereof;

FIG. 5 is a left side view thereof;

FIG. 6 is a right side view thereof;

FIG. 7 is a front view thereof; and,

FIG. 8 is a rear view thereof.

The broken lines in the drawings depict portions of the ice crampon shoe protector that form no part of the claimed design.

1 Claim, 8 Drawing Sheets
